US0D1000401S

(12) **United States Design Patent** (10) **Patent No.:** **US D1,000,401 S**
(45) **Date of Patent:** **** Oct. 3, 2023**

(54) **EQUIPMENT FOR CONTROL OF ELECTRIC POWER**

(71) Applicant: **EcoFlow Inc.**, Shenzhen (CN)

(72) Inventors: **Xi Chen**, Guangdong (CN); **Haibin Zheng**, Guangdong (CN)

(**) Term: **15 Years**

(21) Appl. No.: **35/514,942**

(22) Filed: **May 11, 2022**

(80) **Hague Agreement Data**

Int. Filing Date: **May 11, 2022**

Int. Reg. No.: **DM/222595**

Int. Reg. Date: **May 11, 2022**

Int. Reg. Pub. Date: **Aug. 12, 2022**

(30) **Foreign Application Priority Data**

Feb. 16, 2022 (CN) 202230075389.1

(51) **LOC (14) Cl.** **13-02**

(52) **U.S. Cl.**

USPC **D13/184**

Assistant Examiner — Seth David Kumpf

(57) **CLAIM**

The ornamental design for equipment for control of electric power, as shown and described.

DESCRIPTION

1. Equipment for control of electric power

1.1 : Front

1.2 : Back

1.3 : Left

1.4 : Right

1.5 : Top

1.6 : Bottom

1.7 : Perspective

1.8 : Perspective

Design 1: reproduction 1.1: front view; reproduction 1.2: back view; reproduction 1.3: left view; reproduction 1.4: right view; reproduction 1.5: top view; reproduction 1.6: bottom view; reproduction 1.7: perspective view (front, top, right side); reproduction 1.8: perspective view (back, bottom, left side).

1 Claim, 8 Drawing Sheets
